UNITED STATES PATENT OFFICE

GEORGE L. DANFORTH, JR., AND ALBERT E. PETERSON, OF CHICAGO, ILLINOIS,
ASSIGNORS TO OPEN HEARTH COMBUSTION COMPANY, OF CHICAGO, ILLINOIS, A
CORPORATION OF ILLINOIS

CHECKERWORK

Application filed July 31, 1928. Serial No. 296,581.

This invention relates to a new and improved checkerwork and more particularly to improved brick and checkerwork construction particularly adapted for use in regenerators or the like.

An improved form of checker-brick and checkerwork construction is covered in the Patent No. 1,687,786, granted October 16, 1928, to Albert E. Peterson. The present invention is in the nature of an improvement on the construction of this prior application. In the prior application a single form of brick was shown and in the present application we have shown several additional forms of brick adapted for use in making the checkerwork more stable and uniform where it comes in contact with walls of regenerator chambers, and also where enlarged flues are formed in the checkerwork. The single brick of the prior application was especially adapted for use in forming regenerators of uniform construction where the flues are defined by single bricks on all sides.

It is an object of the present invention to provide new and improved checkerwork and bricks therefor adapted to present a stable and uniform structure.

It is an additional object to provide a construction of this character in which both vertical and horizontal flues of sizes corresponding to multiples of bricks may be formed with the bricks adjacent the flues fully supported.

It is an additional object to provide a construction in which the top courses may be fully supported and rendered stable and may present an approximately level surface.

It is also an object to provide a construction adapted to adequately support the brick which may be located adjacent the regenerator walls.

It is a further object to provide a construction of this character affording both horizontal and vertical flues.

Other and further objects will appear as the description proceeds.

We have shown certain preferred embodiments of our invention in the accompanying drawings, in which—

Figure 1 is a fragmentary perspective view of a checkerwork construction according to our invention;

Figure 2 is a cross section of a checkerwork construction; and

Figures 3, 4, 5 and 6 are perspective views of the different individual brick used in forming our checkerwork.

The brick of Figure 5 is of the type disclosed in the Peterson application above referred to. This brick 11 is of a rectangular shape and in its lower corners has formed the notches 12 and 13. These notches 12 and 13 are of a horizontal extent longitudinally of the brick equal to substantially one-half of the thickness of the brick. The form of brick 14 shown in Figure 6 is similar to that in Figure 4, the notch 15 being identical with the notch 12 of brick 11. The notch 16, however, has a horizontal dimension longitudinally of the brick twice that of the notch 15, or, in other words, equal substantially to the thickness of the brick. It will be understood that the brick 14 is longer than the brick 11 by an amount equal to one-half this length of the notch 16.

Referring now to Figure 3, the brick 17 is of increased width or height and is provided on its lower corners with the notches 18 and 19, which are identical with the dimensions of notches 12 and 13 of brick 11, and also the notch 15 of brick 14. The upper corners of the brick 17 are provided with notches 20 and 21. These notches are of an extent longitudinally of the brick equal to the notches 18 and 19. Vertically of the brick the notches 20 and 21 are of an extent equal to the vertical height of the end portions 22 and 23 of the brick.

Referring now to Figure 4, the lower por-

tion of the brick 24 is similar to the brick 14, being provided with notches 25 and 26 identical with notches 15 and 16. The upper portion of the brick is provided with notches 27 and 28. The notch 27 is identical with the notch 20 of brick 17. The notch 28 is equal in horizontal dimension to the notch 26 and in vertical dimension to the notch 27.

10 These brick are shown incorporated in a checkerwork in Figures 1 and 2. In Figure 1, the upper transverse courses in the rear as shown consists entirely of brick 11 which are the standard form. The brick 17 are shown 15 in the uppermost courses extending along the sides of the upper portion of the open flues shown in Figure 1. The sides of this flue correspond to two brick lengths in extent, less the overlapping notches at the 20 ends. These brick 17 are laid in the plane of the next to the top course of brick and their upper portions extend into the plane of the uppermost course of brick. The upper extensions on the brick 17 thus serve 25 to give lateral support to the brick 14 in the courses crossing them.

The laterally extending brick 14 have their extended ends abutting the plane of the brick forming the side walls of the enlarged flue. The notches 16 thus rest on top of the brick forming the side walls of the flue of which the top courses are flush with the side walls of the flue. The brick 24 are used in the uppermost courses 30 of brick which intersect the middle sides of the flue of which the top courses are formed by brick 11. These brick 24 thus have their long notches 26 resting on brick 11 and their ends flush with the inner wall 35 of the flue.

40 At the lower portion of Figure 1 several larger lateral flues 30 are shown opening into the large vertical flues. These flues 45 are also shown in Figure 2. These flues may extend in all four directions from the enlarged vertical flues and are formed by omitting certain of the brick 11 and by using brick 14 adjacent the flues. These enlarged vertical and horizontal flues form 50 important channels for the introduction of the gases into the checkerwork and serve with particular utility when the smaller upper flues have become clogged with flue dust and the like. The effective life of the checkerwork is thereby increased and the 55 draft losses reduced.

The brick 17 with their upper extensions are particularly important in that they function to render stable the brick crossing them 60 at right angles. This stability is more important than the fact that a substantially uniform top surface is presented. With the increased stability, means may be used for blowing out accumulated flue dust without dislodging the brick.

While we have shown certain preferred forms of the brick by way of illustration and shown them built up into one form of structure, it will be understood that our invention is capable of wide modification and flues may be made having lateral dimensions equal to any desired number of bricks and such additional larger horizontally extending flues may be constructed as may be desired.

70 By the use of the brick of the general form shown, the brick will be fully supported at all times and flush surfaces will be presented in the flues and upon the top of the checkerwork. We contemplate such changes and modifications as come within the spirit and scope of the appended claims.

75 We claim:

1. A brick for checkerwork construction comprising a rectangular shaped member having notched out portions at adjacent corners, one of said notches being substantially twice the extent of the other notch, said larger notch being of an extent in one direction substantially equal to the thickness of the brick.

80 2. A brick for checkerwork construction comprising a rectangular shaped member having notched out portions in all its four corners, the notched out portions on two adjacent corners being of substantially double the extent in one dimension of those on the remaining two corners and being of an extent substantially equal to the thickness of the brick.

85 3. Checkerwork construction for regenerators comprising in combination a plurality of horizontal courses of brick extending at right angles to adjacent courses, to form vertical flues, the brick having notches on their corners whereby the bricks of each course serve to lock the bricks of an adjacent course against displacement, certain of said notches having an extent longitudinally of the brick equal to the thickness of the brick.

90 4. Checkerwork construction for regenerators comprising in combination a plurality of horizontal courses of brick extending at right angles to adjacent courses to form vertical and horizontal flues, the brick having notches on their corners whereby the bricks of each course serve to lock the bricks of an adjacent course against displacement, certain of said brick being of a height as laid in the checkerwork sufficient to give lateral support to brick extending transversely thereof in superposed courses.

95 5. Checkerwork construction for regenerators comprising in combination a plurality of horizontal courses of brick extending at right angles to adjacent courses to form vertical and horizontal flues, the brick having notches on their corners whereby the bricks of each course serve to lock the bricks of the brick.

an adjacent course against displacement, certain of said brick being of a height as laid in the checkerwork sufficient to give lateral support to brick extending transversely thereof in superposed courses, said brick having notches at all four corners.

6. Checkerwork construction for regenerators comprising in combination a plurality of horizontal courses of brick extending at

10 right angles to adjacent courses to form vertical and horizontal flues, the brick having notches on their corners whereby the bricks of each course serve to lock the bricks of an adjacent course against displacement, certain 15 of said brick being of a height as laid in the checkerwork equal to the height of two interlocked vertically adjacent courses of brick, said brick having notches at all four corners, and being laid in the next to the top course 20 and having their upper surfaces substantially in the plane of the top of the top course.

7. Checkerwork construction for regenerators comprising in combination a plurality of horizontal courses of brick extending at 25 right angles to adjacent courses, to form vertical flues, the brick having notches in their corners whereby the bricks of each course serve to lock the bricks of an adjacent course against displacement, said 30 brick being placed to form vertical flues equal in lateral dimensions to a plurality of the brick, and certain of said notches being of an extent equal to the thickness of the brick whereby the brick adjacent said 35 flue are fully supported.

8. Checkerwork construction for regenerators comprising in combination a plurality of horizontal courses of brick extending at right angles to adjacent courses, to form 40 vertical and horizontal flues, certain of said brick being so placed as to form larger vertical flues approximately equal in lateral dimensions to a plurality of brick, and enlarged horizontal flues communicating with 45 said larger vertical flues.

9. Checkerwork construction for regenerators comprising in combination a plurality of horizontal courses of brick extending at right angles to adjacent courses to form vertical and horizontal flues, the brick being stood on edge and provided with notches in certain of their corners whereby the bricks of each course serve to lock the bricks of an adjacent course against displacement, certain 55 of the brick being so placed as to form larger vertical flues having lateral dimensions approximately equal to a plurality of brick.

10. Checkerwork construction for regenerators comprising in combination a plurality of horizontal courses of brick extending at right angles to adjacent courses to form vertical and horizontal flues, the brick being stood on edge and provided with notches in 60 certain of their corners whereby the bricks

of each course serve to lock the bricks of an adjacent course against displacement, certain of the brick being so placed as to form larger vertical flues having lateral dimensions approximately equal to a plurality of brick, and enlarged horizontal flues communicating with said larger vertical flues.

Signed at Chicago, Illinois, this 24th day of July, 1928.

GEORGE L. DANFORTH, JR. 75
ALBERT E. PETERSON.
